UNITED STATES PATENT OFFICE.

JOHN S. BRADY, OF WILKES-BARRE, PENNSYLVANIA.

MACHINE FOR MELTING SNOW.

Application filed March 11, 1925. Serial No. 14,789.

To all whom it may concern:

Be it known that I, JOHN S. BRADY, citizen of the United States, residing at Wilkes-Barre, in the county of Luzerne and State of Pennsylvania, have invented certain new and useful Improvements in Machines for Melting Snow; and I do hereby declare the following to be a full, clear, and exact description of the invention, such as will enable others skilled in the art to which it appertains to make and use the same.

This invention relates to an apparatus mounted on a vehicle for melting snow, by means of which it is possible, in moving this device over snow covered territory, to force the snow by hot blow flames to a heated scoop or chamber, where the steam formed will lead into a condensing duct, acting as a cover for the heating chamber, and then be allowed to run off as condensed steam, thereby utilizing to the maximum all of the fuel heat as expended in heating the scoop plate, forming hot water from melting snow, and making steam.

Obviously, by this invention, a large amount of the heat in the melted snow and steam will be retained in the melting chamber, which would be entirely lost, if the water and steam were allowed to directly exhaust into the atmosphere.

In the drawings,

Fig. 1 illustrates a side elevation view of the snow melting apparatus in assembled form, showing a portion of the condensing device in section.

Fig. 2 is a perspective view of the fuel lines, showing the fuel supply line, supply header, and burners, leading therefrom.

Fig. 3 illustrates a side elevation view of the snow melting scoop, condensing duct, and means for height adjustment of the duct in relation to the fender.

Similar numerals represent the same part in the different views.

Numeral 1 designates a crank ratchet with chain attached to melting device at 14, for the purpose of raising or lowering the snow elevator or melting scoop 2, while 3 represents an adjustable weight at the end of an arm 4, adapted for use as a counterbalance in pivoting the steam condensing duct 5, at the hinge point 6. Numeral 7 designates a sheet metal elevator or scoop casing, while 8 illustrates a swinging door adapted to allow an excess amount of snow or melting ma-

terial to pass from the scoop 2. The numeral 9 designates a fan driven by a small motor 10, adapted to force, if necessary, the steam rising from the melting snow A, up through the steam duct 11 and down through the flexible duct 12, into the condensing duct 5. The flexible duct 12 may be made of canvas or any suitable material, to allow for the swinging of the condensing duct 5 at point 6. Numeral 13 designates a damper in the steam duct 11, to be used for exhaust purposes, or otherwise, if needed.

15 illustrates a supporting frame for the apparatus adapted to be attached or connected to a suitable vehicle 16, preferably designed to carry a fuel supply, such as oil and air as at 17 and 18. The numerals 19 and 20 designate the air and oil supply lines, leading through valves 21 and 22, into a flexible line 23 to the fuel supply header 24, from which a multiplicity of auxiliary burners 25 are designed to extend underneath and in close proximity to the scoop 2, being attached or suitably connected thereto, as by brackets 26. The auxiliary burners 25 may have perforations 27 along the side next to the scoop 2, in order to utilize to the fullest extent the heat generated by the fuel supply for the purpose of heating the scoop or elevator 2. The flexible fuel supply line 23 may be made of any suitable material in order to allow for the pivoting of the melting apparatus on the pivot pin 28, extending through a bracket 29, fastened to the frame work 15. The bracket 29 may be supplied with a multiplicity of pivot pin holes 30, for the purpose of allowing a vertical adjustment of the apparatus.

In the lower side of the condensing duct 5, next to the snow receiving chamber, will be located an opening and sliding damper 31, adapted to open the condensing duct 5, directly to the elevator or receiving chamber whenever the fan 9 is not used.

The portion of the condensing duct 5 ordinarily coming in contact with the snow is preferably designed with an oval shape as at 32, in order to assure a gliding motion over the snow, and attached to the side plates 34 of the duct 5, may be guiding plates or skids 33 of suitable width, adjustably bolted to the plates 34 as at 35.

The numeral 36 designates a set screw adapted to aid in holding the condensing duct 5, in desired position, as established by 110

swinging the duct 5 on hinge point 6, guided by the circular segment bar 37, which is securely fastened at one end to duct plate 34, as at 38. When the condensing duct 5 is 5 raised to a desired height, a few turns of the set screw 36 will operate to hold the device in rigid relation, and if it is desired to limit the movement along the segment at any point, the adjustable weight 39 may be 10 moved along the segment bar 37, and clamped thereto, forming an effective stop.

The steam after passing through the steam duct and cover plate 5, and expending its heat as an additional means of melting snow, 15 will be discharged in the form of condensation through an opening 40 at the base of the duct.

In operation the apparatus will pass over the snow at a suitable speed, the cover 5, or 20 condensing duct, when properly adjusted, will be forced by the snow in an upward direction, thereby allowing the snow to slide up the hot scoop 2 into the heated chamber, the flames bearing on a base line of snow 25 just in front of the apparatus, has made this action comparatively easy. Within the chamber hot water and steam immediately begin to form. The steam is forced into the condensing chamber or cover 5 by means of 30 fan 9, or if fan is not used the steam may be allowed to pass into the condensing chamber through a suitable opening 31, in the bottom of the cover above the snow level, and after the heat in the steam has been used 35 for melting the snow by passing through the hollow cover, it is discharged through opening 40 in the form of condensation. Obviously, by this invention a maximum amount of the total initial heat is used in the melting 40 of the snow, resulting in great economy of time, saving of fuel, and increased efficiency generally. The economy in time resulting from the use of this invention, would allow 45 a greatly increased area of snow covered territory to be thoroughly cleared, at a minimum of cost.

What I claim is:—

1. In a snow scoop mounted on a vehicle, 50 the combination with a snow melting device, consisting of a container having a heated scoop upon which the snow is forced thereby, forming hot water and steam, of a condensing chamber adapted to form a cover for the container, and means for admitting the steam to the condensing chamber.

2. In a snow scoop mounted on a vehicle, 55 the combination with a snow melting device,

consisting of a container having a heated scoop upon which the snow is forced thereby, forming hot water and steam, of a condensing chamber adapted to form a cover for the container, and means for admitting the steam to the condensing chamber, the said condensing chamber having an opening in the end adapted as a discharge for condensation.

3. In a snow scoop mounted on a vehicle, the combination with a snow melting device, consisting of a container having a heated scoop upon which the snow is forced thereby, forming hot water and steam, of a condensing chamber adapted to form a cover for the container, and means for admitting the steam to the condensing chamber the said condensing chamber having an opening 75 in the end adapted as a discharge for condensation, of means for adjusting the condensing chamber cover in relation to the container and upper snow surface.

4. In a snow scoop mounted on a vehicle, 80 the combination with a snow melting device, consisting of a container having a heated scoop upon which the snow is forced thereby, forming hot water and steam, of a condensing chamber adapted to form a cover 85 for the container, and means for admitting the steam to the condensing chamber, the said condensing chamber having an opening in the end adapted as a discharge for condensation, of means for adjusting the condensing chamber cover in relation to the container and upper snow surface, and means to adjust the height of the container in relation to the snow covered surface.

5. In a snow scoop mounted on a vehicle, 90 the combination with a snow melting device, consisting of a container having a heated scoop upon which the snow is forced thereby, forming hot water and steam, of a condensing chamber adapted to form a cover 100 for the container, and means for admitting the steam to the condensing chamber, the said condensing chamber having an opening in the end adapted as a discharge for condensation, of means for adjusting the condensing chamber cover in relation to the container and upper snow surface, and means to adjust the height of the container in relation to the snow covered surface of 105 skids adjustably attached to the sides of 110 the condensing chamber, adapted to aid the cover to glide over the surface of the snow.

In testimony whereof I affix my signature.
JOHN S. BRADY.
